UNITED STATES PATENT OFFICE.

HERBERT H. DREW, OF WATERLOO, WISCONSIN, ASSIGNOR OF ONE-HALF
TO EDWIN M. SNOW, OF WATERLOO, WISCONSIN.

RAILWAY-CAR TRUCK.

No. 856,626.

Specification of Letters Patent.

Patented June 11, 1907.

Application filed March 25, 1907. Serial No. 364,236.

To all whom it may concern:

Be it known that I, HERBERT H. DREW, a citizen of the United States, and a resident of Waterloo, in the county of Jefferson and State of Wisconsin, have invented certain new and useful Improvements in Railway-Car Trucks; and I do hereby declare that the following is a full, clear, and exact description thereof.

10 The improvements consist in what is herein shown, described and claimed; the object of the invention being to provide railway-car trucks of common knowledge with simple, economical running-gear designed to automatically compensate for differences in the radius of track-curves, thus reducing friction and preventing spread of track-rails.

Figure 1 of the accompanying drawings represents a plan view, partly in horizontal section, of a fragment of a railway-car truck having running-gear in accordance with my invention, the view being indicated by lines 1-1 in the figure next in order, and Figs. 2 and 3 sectional views indicated by lines 25 2-2 and 3-3 respectively in Fig. 1.

Referring by letter to the drawings, A indicates the framework of a railway-car truck as ordinarily constructed, B the journal-boxes and C the body-boglster of same. Each 30 wheel D of the truck is fast on an independent short axle E, the inner end of which axle has play in an arched slot of a hanger F attached to cross-timbers of the truck-frame, and provision is had in the journal-boxes B 35 to prevent cramping of said axles, as by a convex fit of the brasses with the box covers, an instance of the same being well shown in Fig. 2.

When the truck-wheels are running on the 40 rails of a track-curve, the tendency of their flanges to bind against said rails results in an automatic compensating adjustment of said wheels and their axles, inasmuch as there is forward swing and tilt of one axle of each 45 pair and rearward swing and tilt of the other axle of said pair, owing to the arched play-slots provided in the hanger for said axles.

In pivotal connection with the hanger aforesaid are paired arms G that normally

50 abut stops with which said hanger is preferably provided, one arm being forward and the other rearward of an axle. The arms of each pair are coupled and spring-controlled to resist play of the corresponding short axle in either direction and thus said axle and wheel therewith are held in normal position central of the hanger-slots until such time as the friction of the wheel-flange on a track-rail is sufficient to overcome the power of the controlling spring. In the showing one of 60 the arms G in each pair is coupled to a casing H containing a spring I, and the companion arm is coupled to a rod J that plays in the casing and has a head in opposition to an end of the spring, the latter being under tension 65 in said casing.

I claim:

1. A railway-car truck having each wheel thereof provided with an independent short axle with which it is rigid, journal boxes for 70 the axles, and hangers having arched slots in which the inner ends of the axles are loosely supported, provision being had to prevent cramping of said axles incidental to play of their inner ends in the hanger-slots. 75

2. A railway-car truck having each wheel thereof provided with an independent short axle with which it is rigid, journal-boxes for the axles, hangers having arched slots in which the inner ends of the axles are loosely 80 supported, provision being had to prevent cramping of said axles incidental to play of their inner ends in the hanger-slots, and coupled spring-controlled arms arranged in pivotal connection with the hangers to oppose each axle in opposite directions and thereby resist movement of same out of normal position central of the corresponding hanger-slot. 85

In testimony that I claim the foregoing I 90 have hereunto set my hand at Waterloo in the county of Jefferson and State of Wisconsin in the presence of two witnesses.

HERBERT H. DREW.
